DESIGN.

E. CREE & C. S. COURT.

HANDLE FOR BUTTON HOOKS OR SIMILAR ARTICLES.

No. 28,555.

Patented May 10, 1898.

UNITED STATES PATENT OFFICE.

EUSTACE CREEES AND CHARLES S. COURT, OF PROVIDENCE, RHODE ISLAND,
ASSIGNORS TO THE WAITE, THRESHER COMPANY, OF SAME PLACE.

DESIGN FOR A HANDLE FOR BUTTON-HOOKS OR SIMILAR ARTICLES.

SPECIFICATION forming part of Design No. 28,555, dated May 10, 1898.

Application filed March 19, 1898. Serial No. 674,541. Term of patent 3½ years.

To all whom it may concern:

Be it known that we, EUSTACE CREEES and CHARLES S. COURT, citizens of the United States, residing at Providence, in the State of Rhode Island, have invented and produced a new and original Design for a Handle for Button-Hooks or Similar Articles, of which the following is a specification, reference being had to the accompanying drawings, forming a part thereof.

Figure 1 represents a side view of a handle, showing our new design. Fig. 2 represents a longitudinal section thereof.

As shown in the drawings, the leading or material feature of our design consists in the circular bead *a* at the forward end of the handle, the opposite raised ribs *b b*, the opposite inwardly-directed foliated scrolls *c c*, and the smaller scrolls *c' c'*, which form the boundary of the convex panel *d*, and within the space inclosed by the raised boundary edges *b b* and near the circular bead *a* is arranged the representation of a rose or other flower *e*, with the three leaves *f f f*, and between the leaves *f* and the ends of the foliated scrolls *c c* are arranged the foliated scrolls *g g*, and between the foliated scrolls *g g* and the raised boundary ribs *b b* are arranged the rows of beads *h h*. Along the edge of the handle are arranged the curved rows of beads *i i*, beyond the ends of which are arranged the inwardly-

curved foliated scrolls *j j*, and between the ends of the said scrolls *j j* is arranged the bead *k*, and in the space embraced between the rows of beads *i i* and the foliated scrolls *j j*, at the opposite edges of the handle, are arranged the curved rounded and tapering ornamental projections *l l*, which are embraced at their edges by the foliated scrolls *m m*, and between the rounded ends of the ornamental projections *l l* is arranged the rounded tapering ornamental projection *n*, having a foliated scroll *o* at its rounded end, and between the said rounded tapering ornamental projections *l l* and *n* are arranged the rows of graduated beads *p p' p''*, and at the outer end of the handle, beyond the inwardly-curved ends of the foliated scrolls *j j*, are arranged the inwardly-curved foliated scrolls *r r' r'*, which radiate from the apex *s*.

Having now described our invention, what we claim as new, and desire to secure by Letters Patent, is—

The design for a handle for button-hooks and similar articles herein shown and described.

EUSTACE CREEES.
CHARLES S. COURT.
